UNITED STATES PATENT OFFICE

121,485

DESIGN FOR A COMBINED ADVERTISING
AND VENDING DISPLAY STAND

Abraham N. Spanel, New York, N. Y.

Application March 26, 1940, Serial No. 91,240

Term of patent 14 years

To all whom it may concern:

Be it known that I, Abraham N. Spanel, a citizen of the United States, and residing at New York, in the county of New York and State of New York, have invented a new, original and ornamental Design for a Combined Advertising and Vending Display Stand, of which the following is a specification, reference being had to the accompanying drawing, forming part thereof, wherein:

Figure 1 is a top plan view of a combined advertising and vending display stand, showing my new design; and

Figure 2 is a side elevational view thereof.

The design is characterized by a combined advertising and vending display stand having a multiple series of cylinders for holding goods on display, the cylinders being arranged to present a stepped-up or conical tier configuration substantially as shown.

I claim:

The ornamental design for a combined advertising and vending display stand, substantially as shown and described.

ABRAHAM N. SPANEL.
